(57) **CLAIM**

The ornamental design for an outrigger for crane truck, as shown and described.

DESCRIPTION

FIG. 1 is a perspective view of an outrigger for crane truck showing our new design;

FIG. 2 is a right side view thereof attached to the crane truck;

FIG. 3 is a left side view thereof attached to the crane truck;

FIG. 4 is a plan view thereof attached to the crane truck;

FIG. 5 is a bottom view thereof attached to the crane truck;

FIG. 6 is a front view thereof attached to the crane truck;

FIG. 7 is a front view of the outrigger for crane truck;

FIG. 8 is a rear view thereof;

FIG. 9 is a plan view thereof;

FIG. 10 is a bottom view thereof;

FIG. 11 is a right side view thereof; and,

FIG. 12 is a left side view thereof. The broken line in the drawings are included for the purpose of illustrating portions of the outrigger for crane truck and form no part of the claimed design.

1 Claim, 5 Drawing Sheets
